CLAIM

The ornamental design for an art supply package, as shown and described.

DESCRIPTION

FIG. 1 is a top perspective view of an art supply package showing my new design in an exploded condition; FIG. 2 is an enlarged top plan view thereof; FIG. 3 is a front elevation thereof, the undisclosed rear portion being a mirror image of the front shown; FIG. 4 is an end elevation thereof, the opposite end being a mirror image of the end shown; FIG. 5 is a bottom plan view at a reduced scale; and FIG. 6 is a cross section taken along line 6—6 of FIG. 2.

FIG. 1

FIG. 2

FIG. 3

FIG. 4

FIG. 5

FIG. 6
